UNITED STATES PATENT OFFICE.

ARTHUR MERRITT AND EUGENE F. AUCAIGNE, OF NEW YORK, N. Y.

DESIGN FOR A CLOCK-CASE.

SPECIFICATION forming part of Design No. 22,011, dated November 22, 1892.

Application filed October 27, 1892. Serial No. 450,182. Term of patent 7 years.

To all whom it may concern:

Be it known that we, ARTHUR MERRITT and EUGENE F. AUCAIGNE, citizens of the United States, residing in the city and State of New York, have invented a new Design for a Clock-Case, of which the following is a specification.

The leading feature of this design consists in a truncated conical case with a tapering 10 and ribbed extension at one side, the clock-face being the smaller end of the truncated cone.

The design of the case is represented in the accompanying drawing, in which—

Figure 1 is a face view, and Fig. 2 is a side 15 view.

The edges *a* of the case are conical, and the

smaller or truncated end of the case receives the clock-face figures. The tapering extension *b* at one side of the case has curved edges and is rounded at the extreme end and perforated and the surface is undulating with ribs at the edges. 20

We claim—

The design for a clock-case, herein shown and set forth.

Signed by us this 20th of October, 1892.

ARTHUR MERRITT.
EUGENE F. AUCAIGNE.
